Primary Examiner — Mitchell I. Siegel

(74) Attorney, Agent, or Firm — Steven M. Greenberg,
Esq.; Shutts & Bowen LLP(57) **CLAIM**

The ornamental design for a flange blade putter, as shown and described.

DESCRIPTION

FIG. 1 is a top front perspective of a putter according to our invention;

FIG. 2 is a bottom front perspective view of the putter of FIG. 1;

FIG. 3 is a front view of the putter of FIG. 1;

FIG. 4 is a back view of the putter of FIG. 1;

FIG. 5 is a left view of the putter of FIG. 1;

FIG. 6 is a right view of the putter of FIG. 1;

FIG. 7 is a top view of the putter of FIG. 1; and,

FIG. 8 is a bottom view of the putter of FIG. 1.

The broken lines shown are included for the purpose of illustrating unclaimed subject matter and forms no part of the claimed design.
